UNITED STATES PATENT OFFICE.

HUBERT VAN BREE, OF RACINE, WISCONSIN.

MOTOR-DRIVEN HAIR-CLIPPER.

1,357,364.

Specification of Letters Patent. Patented Nov. 2, 1920.

Application filed October 27, 1919. Serial No. 333,799.

To all whom it may concern:
Be it known that I, HUBERT VAN BREE, a citizen of the United States, and resident of Racine, in the county of Racine and 5 State of Wisconsin, have invented new and useful Improvements in Motor-Driven Hair Clippers, of which the following is a description, reference being had to the accompanying drawings, which are a part 10 of this specification.

The invention relates to motor driven hair clippers.

One of the objects of this invention is to provide a motor driven hair clipper in 15 which the housing for the driving connection to the movable blade is of oblong shape to form a handle which may be readily gripped in the hand to allow wrist, arm and finger motion in the use of the clipper. 20 Another object of the invention is to provide a hair clipper in which there are less teeth on one of the blades than on the other to secure a better cutting operation.

A further object of the invention is to 25 provide a simple and compact form of driving connection between the rotating shaft and the movable blade of the clipper.

A further object of the invention is to 30 provide a combination and arrangement of parts of the clipper so that it may be readily taken apart or assembled.

A further object of the invention is to 35 provide a simple and efficient safeguard for the parts within the housing to prevent hair, dust or other foreign matter from working into the housing.

A further object of the invention is to 40 provide the handle with an opening in the small end for hanging the clipper on a hook or other support when not in use.

Another object of the invention is to provide a simple quickly detachable connection between the sheath of the flexible drive shaft and the housing. 45

The invention further consists in the several features hereinafter set forth and more particularly defined by claims at the conclusion hereof.

In the drawings: Figure 1 is a top view 50 of the device embodying the invention with the cover plate removed, parts being broken away and parts being shown in section; Fig. 2 is an elevation view of the device; Fig. 3 is a section taken on the line 3—3 55 of Fig. 1 with the crank pin in a different position; Fig. 4 is a section taken on the

line 4—4 of Fig. 1; Fig. 5 is a bottom view of the front end of the device; Fig. 6 is a bottom view of the compression plate.

Referring to the drawings, the numeral 60 7 designates the housing generally. This housing has a hollow interior 8 and a cover plate 9 resting upon marginal edge flanges 10 of said housing. At its rear end the housing is provided with a bore 11 leading 65 to the interior and with an opening 12 by which the device may be conveniently suspended from a hook or other suitable support when not in use. The main body portion of the housing is preferably of an oblong 70 shape whereby the operator may readily manipulate the clipper by securing a finger or handhold on the sides 13 of said housing, while the rear end has an inwardly curved side 14 which may be engaged by 75 the little finger of the operator if desired.

The housing has straight flat top and bottom sides substantially parallel to each other and its front end 15 is inclined and to this inclined face a fixed clipper blade 16 80 is secured by screws 17. This form of connection insures a rigid mounting of the blade on the housing and permits of a handhold close to the blade, thus securing efficient control of the clipper. 85

A movable blade 18 cooperates with the blade 16 to perform the cutting operation. This blade 18 has a bearing surface running on the upper surface of the blade 16 and is guided in its movement with respect to the 90 blade 16 by tongues 19 running in a transverse slot or groove 20 in said blade 16. The blade 18 is held against the blade 16 by means of a compression plate 21 mounted on the housing and having its forward edge portions 21' yieldingly maintained against the movable blade by means of a spring 22 mounted on a stud 23 carried by the housing and projecting through the casting, said spring being interposed between 95 said plate and an adjustable thumb nut 24 on the upper threaded end of said stud so that the pressure exerted by the plate upon the blade may be varied as desired. The compression plate 21 has ears or flanges 25 fitting over the sides of the housing to hold 100 said plate in proper position with respect to the blade 18.

The usual flexible drive shaft 26 driven from an electric motor or other suitable 110 source of power is provided with a bearing sleeve 27 fitting within the bore 11 and hav-

ing an annular groove 28. The housing 7 has a bore 29 therein communicating with the bore 11 through a contracted opening 30 forming a seat for a clutch ball 31 which is held in locking engagement with the groove 28 by a spring 32 interposed between the ball and a set screw 33 mounted in the threaded upper end of the bore 29. The end 34 of the shaft 26 is provided with the usual key 35 engaging in a key slot 36 in the hollow end of a shaft 37. By this construction the shaft 34 may be quickly secured to or detached from the shaft 37 and the sheath secured to or detached from the 15 housing.

The shaft 37 is journaled at one end in a bushing 38 secured in the inner end of the bore 11 by a set screw 38' and at its other end in a bushing 39 in a bearing lug 40, said 20 bushing 39 contacting with a shoulder on the shaft 37 to form an end thrust bearing. This shaft 37 has a worm 41 formed integral therewith and meshing with a worm wheel 42 journaled on a stud shaft 43 mounted in 25 the bottom of the housing. This worm carries a crank pin 44 upon which a sliding block 45 is pivotally mounted. The block 45 runs in a slot 46 in one end of a rocking lever 47 which is pivotally mounted intermediate its ends upon the stud or post 23. The other end 48 of the lever 47 extends beyond the housing and has rounded edges 48' which engage the sides of a slot 49 centrally located in the rear edge of the blade 18. 30 Where the lever projects through the housing a notch 50 is provided to permit free swinging of the lever, and to prevent any hair, dust or foreign matter from working into the housing through this space, felt 35 wicks 51 containing oil or other suitable packing members are seated in recesses 52 in the housing and bear against the rounded portion 53 of the lever adjacent its pivot, said wicks being compressed to some extent 40 between the housing and its cover to provide an efficient seal, though the compression plate also assists in excluding foreign matter 45 from the housing.

By this construction the rotation of the 50 shafts 26 and 37 will through the worm gearing 41, 42 and crank 44 and block 45 oscillate the lever 47, which will reciprocate the blade 18 transversely of the fixed blade 16.

55 To obtain more efficient cutting of the hair the fixed blade 16 is provided with a greater number of teeth than the movable blade 18 and in the present instance I have shown two teeth on the fixed blade to one on the 60 movable blade. By this arrangement the spacing between the teeth of the lower comb blade 16 being smaller, the hair will be split up into smaller tufts for cutting and thus make the cutting easier. The stroke of the 65 cutting blade is also made longer than the

distance between two teeth on the stationary blade, which insures the teeth in the upper blade fully clearing those in the lower blade before reverse action. The underside of the blade 16 is provided with corrugations 54. 70 With the above construction of blades the teeth in both cutting plates clear and cut clean without a pull on the hair.

In the above construction removal of the 75 compression plates permits the blade 18 being lifted off of the blade 16 and removal of the cover plate permits the lever to be lifted from its pivot, the block to be removed from the crank pin and the worm wheel to be removed from its pivot and out 80 of engagement with the worm for the purpose of cleaning if desired.

A guard 55 fits over the teeth of the cutter when the device is not in use.

I desire it to be understood that this invention is not limited to any specific form or arrangement of parts except in so far as such limitations are specified in the claims.

What I claim as new and desire to secure by Letters Patent is:

90 1. In a motor driven clipper, the combination of a housing for the cutter driving mechanism, a relatively fixed cutter secured to said housing, a movable cutter mounted on the fixed cutter, driving mechanism for the movable cutter including an oscillatory lever projecting through an opening in said housing, and packing strips in the housing adjacent the pivot point of the lever to prevent foreign matter from entering into said 95 housing.

100 2. In a motor driven clipper, the combination of an oblong-shaped housing having an inclined front end and forming a handle having a cavity therein communicating through a slot with the front end of the housing, a relatively fixed cutter secured to said inclined end, a movable cutter bearing on the fixed cutter, a pivot post vertically mounted in the slot, a flat oscillatory lever 105 extending from within the cavity through said slot and operatively connected to said movable cutter and journaled on said post, a gear drive within the cavity for operating said lever, and a cover plate for said cavity. 110

115 3. In a motor driven clipper, the combination of a flat-faced housing having an inclined front face, a fixed cutter secured to said face, a post disposed at right angles to the top of the housing and above said face, 120 a movable cutter mounted on the fixed cutter, an oscillatory member mounted on the post and operatively connected with the movable cutter, means within the housing for operating said lever, and a compression plate 125 mounted on the post with its upper surface disposed substantially parallel to and close to the upper face of the housing.

130 4. In a motor driven clipper, the combination of a flat-faced oblong housing having a

rearward extension provided with a curved side forming a finger hold and an opening adjacent said side for suspending the device from a support, a fixed cutter on the front 5 end of the housing, a movable cutter adjacent the fixed cutter, an oscillatory lever projecting through an opening in said housing and operatively connected with the movable cutter, means within the housing for

operating said lever, and means at the opening through which said lever passes to exclude foreign matter from said housing. 10

In testimony whereof, I affix my signature, in presence of two witnesses.

HUBERT VAN BREE.
